UNITED STATES PATENT OFFICE

164,172

AIR CONDITIONER CABINET OR SIMILAR ARTICLE

Robert S. Herbst, East Orange, and Byron E. Freitag, River Edge, N. J., assignors to General Electric Company, a corporation of New York

Application March 30, 1951, Serial No. 14,672

Term of patent 14 years

(Cl. D62—4)

To all whom it may concern:

Be it known that we, Robert S. Herbst and Byron E. Freitag, citizens of the United States, residing respectively at East Orange, State of New Jersey, and at River Edge, State of New Jersey, have invented a new, original, and ornamental Design for an Air Conditioner Cabinet or Similar Article, of which the following is a specification, reference being had to the accompanying drawing, forming a part thereof.

The single figure of the drawing is a perspective view of an air conditioner cabinet or similar article embodying our new design. The opposite end wall of the cabinet is of the same design as the one shown and the rear side of the cabinet is substantially plain.

We claim:

The ornamental design for an air conditioner cabinet or similar article, substantially as shown and described.

ROBERT S. HERBST.
BYRON E. FREITAG.
